UNITED STATES PATENT OFFICE

OLIVER J. MOUSSETTE, SR., OF RICHMOND HILL, NEW YORK

WASHING MACHINE

Application filed August 17, 1931. Serial No. 557,616.

This invention has for its object the provision of a simple, compact, inexpensive and highly efficient washing machine. The invention is illustrated in the accompanying drawings and will be hereinafter first fully described and then more particularly defined in the appended claims.

In the drawings,

Figure 1 is a vertical section of a washing machine embodying the invention,

Fig. 2 is a horizontal section on the line 2—2 of Fig. 1,

Fig. 3 is a top plan view, with parts broken away and in section, of the operating mechanism,

Fig. 4 is an enlarged detail elevation of a portion of the operating mechanism,

Fig. 5 is a vertical section through the mechanism for transmitting motion to a wringer,

Fig. 6 is a detail section on the line 6—6 of Fig. 4, and

Fig. 7 is a detail of a clutch which is included in the mechanism for transmitting motion to a wringer.

In carrying out the invention, there is provided a supporting frame 1 which is preferably of a rectangular outline and is mounted upon casters 2 whereby it may be moved from place to place and easily moved out of the way when it is not in use. The frame is preferably of skeleton form and includes a plurality of legs and a rim 3 secured on and connecting the upper ends of the legs. There is also a shelf 4 provided below the top of the frame and secured to and carried by the legs in any convenient manner.

Resting upon the top of the frame and preferably bolted thereto is a tank 5 usually of cylindrical form and equipped with a removable cover 6. At the center of the tank is a vertically disposed bearing 7 through which extends the dolly shaft 8, a stuffing box 9 being disposed around the shaft within the tank, as shown in Fig. 1, to prevent leakage. There is also a drain pipe 10 fitted in the bottom of the tank and extending to a point outside the supporting frame where it is equipped with a valved outlet 11 so that the liquid in the tank may be drawn off when desired. Fitted on

the upper end of the dolly shaft 8 is a head 12 secured to the shaft by a set screw 13 or other convenient means, and suspended from this head is a follower or plunger 14. The plunger fits slidably about the dolly shaft and consists of a circular plate having perforations 15 therethrough throughout its entire extent and reinforced against buckling by radial ribs 16 on its upper surface, as shown. The hub member 17 of the plunger has bolts 18 secured therein, and said bolts rise through the head 12 and are slidably fitted in said head, being held against withdrawal by nuts 19 fitted on their upper ends and turned home against the head or a flange thereon, as will be understood. A coiled expansion spring 20 is disposed between the head and the plunger and yieldably holds the plunger in its lowermost position relative to the dolly shaft and the head.

Mounted upon the shelf 4 is an electric motor 21 which may be of any approved form and is illustrated in a conventional manner only. The armature shaft 22 of this motor extends therefrom to be coupled by a sleeve 23 to a worm shaft 24, the latter being journaled in a gear case 25 supported upon the shelf 4 and being provided within the gear case with a worm 26 meshing with a worm gear 27, also disposed within the gear case and arranged above the worm shaft. The worm gear is secured upon a transmission shaft 28 which extends through lateral sleeves or bearings 29 on the sides of the gear case and, at one end, is equipped with a crank disk 30 while, at its opposite end it is equipped with a bevel pinion 31. The crank disk 30 carries an eccentric wrist pin 32 which is journaled in a block 33 disposed within a slot 34 of a lever 35 which is pivoted at one end upon a bearing bracket or post 36 erected on the platform 4. The free end of the lever 35 is forked, as indicated at 37 in Fig. 3, and to said free forked end is pivoted a link 38 which extends upwardly from the lever and has its upper end pivotally mounted upon a stud 39 extending from a block 40 which is secured adjustably upon the dolly shaft, as shown in Fig. 6, the end of the lever being retained on the stud 100.

by a nut 41 and washer 42 in an obvious manner. It will be readily understood that, when the shaft 28 is rotated, the wrist pin 32 will cause the block 33 to reciprocate in the slot 34 of the lever 35 and, as the block also follows the orbital movement of the wrist pin, a vibratory movement will be imparted to the lever, and this in turn will be transmitted to the dolly shaft so that the latter will be reciprocated vertically. The shaft 28 and the crank disk 30 rotate in the direction indicated by the arrow in Fig. 1, so that when the dolly shaft is descending the movement will be relatively slow and steady, but the upward movement will be quick and rapid owing to the difference in the length of the arcs traversed by the several portions of the lever during the two movements. The downward movement will, of course, cause the plunger to exert pressure upon the clothes disposed in the tank, and the spring 20 will permit the plunger to yield to the impact, so that the probability of damaging the clothes or other articles will be minimized. The upward movement, being quick and sharp, will create a suction below the plunger which will cause the water and other cleansing agents to rise rapidly through the clothes so that they are quickly relieved of all dirt and other foreign matter. As indicated in Figs. 3 and 4, roller bearings are preferably provided around the wrist pin 32 and the block 33 is given a circular form to reduce the area of contact and minimize friction.

35 The pinion 31 is disposed within a bracket or housing 43 which is secured on the shelf 4 at one side thereof and furnishes a step bearing for a vertical shaft 44 upon which is a bevel pinion 45 meshing with the pinion 31, as shown in Fig. 5. The shaft 44 rises through a sleeve or tubular housing 46 to a gear case 47 which is supported by a bracket 48 resting on the cap 49 which closes the upper end of the tube 46. The bracket 48 not only furnishes a rest for the gear case 47 but also provides a support upon which a clothes wringer may be mounted, and the clothes wringer may be operated in either direction by power transmitted from the shaft 44. In the gear case 47, above the upper end of the shaft 44, is mounted a shaft 50 which is journaled in the sides of the gear case and projects therefrom to be secured to or connected with the wringer rolls. Secured on the upper end of the shaft 44 within the gear case 47 is a bevel gear 51, and loosely mounted upon the shaft 50 are oppositely disposed bevel gears 52 and 53 which mesh with the gear 51 at diametrically opposite points thereof. Obviously, the gears 52 and 53 will rotate in opposite directions, and the shaft 50 will rotate in one or the opposite direction accordingly as one or the other of said gears is made fast thereto. To cause the gears to selectively actuate the shaft 50, a

clutch sleeve 54 is splined upon the shaft between the gears, as clearly shown in Fig. 5, said clutch sleeve being provided at both its ends with lugs or projections 55 adapted to engage with lugs 56 on the opposed faces of the gears so that the engaged gear will be rotated and will transmit motion to the shaft 50. To shift the clutch sleeve into engagement with the desired gear, there is provided a crank 57 on the lower end of a rock shaft 58 which is journaled in the top of the gear case and equipped with a handle 59. The crank 57 carries a depending stud or crank pin 60 which fits within an annular groove 61 in the clutch sleeve, so that if the crank be rocked the sleeve will be shifted endwise along the shaft 50 in an obvious manner.

In use, the plunger is removed from the dolly shaft, and the clothes or other articles to be washed are placed in the tank 5, together with a suitable quantity of water to which may be added soap or other detergents. The plunger is then again fitted over the upper end of the dolly shaft and secured thereto, whereupon the motor circuit is closed and the described movements imparted to the working parts. The machine operates very easily and quietly and clothes have been very thoroughly cleaned in a very short period of time. It will be understood, of course, that when the washing machine is operating, the wringer is inoperative and the clutch sleeve 54 is set in a neutral position, as illustrated in Fig. 5.

Having thus described the invention, I claim:

1. A washing machine comprising a tank, a dolly shaft mounted therein, means for vertically reciprocating the dolly shaft, a head secured on the shaft, a plunger fitted slidably around the shaft, suspending rods secured to the plunger and fitted slidably through the head, and an expansion spring disposed about the shaft between the head and the plunger and normally holding the plunger in its relatively lowest position.

2. In a washing machine, the combination of a tank, a dolly shaft therein, a plunger carried by the dolly shaft, a lever fulcrumed at one end below the tank, a link connecting the other end of the lever with the dolly shaft, the lever having a longitudinal slot between its ends, a crank disk disposed adjacent the side of the lever, a wrist pin on the crank disk extending into the slot in the lever, a block on the wrist pin traveling in the slot on the lever, and means for rotating the crank disk whereby the lever and shaft will have a relatively slow downward movement and a relatively quick upward movement.

In testimony whereof I affix my signature.

OLIVER J. MOUSSETTE, Sr. [L. S.]
